US00D681391S

(12) **United States Design Patent**
Agren

(10) **Patent No.:** **US D681,391 S**
(45) **Date of Patent:** **** May 7, 2013**

(54) **HAND MIXER**

- (75) Inventor: **Christian Agren**, Stockholm (SE)
- (73) Assignee: **Aktiebolaget Electrolux**, Stockholm (SE)
- (**) Term: **14 Years**
- (21) Appl. No.: **29/431,372**
- (22) Filed: **Sep. 6, 2012**

Related U.S. Application Data

- (62) Division of application No. 29/405,153, filed on Oct. 28, 2011, now Pat. No. Des. 667,682.
